UNITED STATES PATENT OFFICE.

HENRY HURTER, OF ST. LOUIS, MISSOURI, ASSIGNOR TO FULTON IRON WORKS COMPANY, OF ST. LOUIS, MISSOURI, A CORPORATION OF DELAWARE.

CRUSHING-MILL.

1,280,038.

Specification of Letters Patent. Patented Sept. 24, 1918.

Application filed November 5, 1917. Serial No. 200,302.

To all whom it may concern:

Be it known that I, HENRY HURTER, a citizen of the United States of America, a resident of the city of St. Louis, in the State of Missouri, have invented certain new and useful Improvements in Crushing-Mills, of which the following is a full, clear, and exact description, reference being had to the accompanying drawings, forming a part of this specification.

My invention relates to improvements in crushing mills comprising a pair of crushing rolls, one of which is movable toward and away from the other, the movable roll being tiltable so as to exert a substantial uniform pressure on an irregular mass of cane, or other material, passing between the rolls. For example, if a relatively large mass of material is fed between the end portions of the opposing rolls, the upper roll will tilt and remain in firm contact with the material near the opposite ends of the rolls. The present invention is an improvement on the crushing mill shown in the patent to J. F. O'Neil, 1,208,632, December 12, 1916.

The main object of this invention is to generally improve the mill shown in the above mentioned patent by simplifying the structure, rendering it more durable and at the same time enabling the tiltable elements to perform their functions more easily and more effectively. The earlier structure includes a tiltable crushing roll having journals, bearings seated on the journals, yielding caps seated on the bearings and a tiltable scraper connected to said yielding caps, said scraper being fitted to the periphery of the tiltable crushing roll. The object is to allow one of the crushing rolls to tilt, as previously pointed out, and to maintain the scraper in parallelism with the axis of the tiltable roll. However, in the prior structure, the bearings for the tiltable roll are firmly guided so they cannot tilt with the roll, and this is quite undesirable. Furthermore, the yielding caps are fitted to flat upper faces of the bearings, and the tiltable scraper is connected to these caps. In other words, the tiltable scraper is connected to caps which cannot tilt with the tiltable roll, and the latter is fitted to non-tilting bearings. My objects are to enable the bearings to tilt freely with the tiltable roll, and to connect the scraper with

the tiltable bearings, thereby maintaining the bearings in firm engagement with the journals of the tiltable roll and also maintaining the scraper in parallelism with the axis of said roll.

Figure I is a vertical section of a crushing mill constructed in accordance with my invention.

Fig. II is a section on line II—II, Fig. I.

Fig. III is a fragmentary rear view of the upper portion of the mill, showing the side opposite to that illustrated in Fig. I.

Fig. IV is a fragmentary section taken approximately through the center of one of the side frames.

A designates side frames, each provided with a pair of guide members 1. A lower crushing roll 2 is rotatably mounted between the side frames. 3 designates a tiltable crushing roll, arranged above the roll 2 and provided with journals 4 which lie between the guide members 1. Bearings B are slidably mounted between the guides 1 and firmly fitted to the journals 4. The opposite-side faces of each bearing B are closely fitted to the guide members 1, as shown in Fig. IV, and each bearing is provided with guide flanges 5 normally separated from the guide members 1, as shown most clearly in Fig. III. It is important to note that the guide flanges 5 are not closely fitted to the guide members, and that the bearings B are therefore free to tilt with the roll 3.

Stationary caps 6 are seated upon the upper ends of the guide members 1 and rigidly secured thereto by means of rods 7 extending from the guide members and nuts 8 on the outer ends of said rods. Each cap 6 is provided with a fluid receiving chamber 9 closed by a plug 10 and having a port 11 for the admission and discharge of fluid under pressure. Plungers 12, mounted in the chambers 9, extend downwardly from the stationary caps 6 and engage the top faces of the tiltable bearings B. To allow the bearings to tilt freely with the tiltable roll, the plungers 12 are formed with convex bottom faces which engage concave faces on the bearings, as shown in Fig. IV. The fluid under pressure acting upon the plungers 12 maintains the tiltable bearings B in firm engagement with the journals 4 of the tiltable roll. The fluid actuated plungers yield to allow the crushing roll 3 to tilt and move.

toward and away from the other roll, and the bearings B tilt freely with said roll 3.

The crushing rolls are preferably grooved, as shown in Figs. I and III, and they may 5 be rotated by any suitable power mechanism to crush the material which passes between them.

13 designates a scraper blade fitted to the periphery of the tiltable roll 3, said blade 10 being corrugated to conform to the configuration of the grooves in said roll. The scraper blade 13 is fixed to a plate 14, the latter being fixed to a rod 15 having round end portions mounted in bearings 16 at the 15 outer ends of arms 17. These arms 17 are rigidly secured to the tiltable bearings 5 which move with the tiltable crushing roll 3. By constructing and arranging the parts in this manner, I provide a scraping device 20 which partakes of the movements of the crushing roll 3 when the latter is tilted by the material to be crushed. The position of the scraper blade 13 with respect to the axis of the roll 3, is not changed when said roll 25 is tilted nor when it moves in a straight line toward and away from the other roll. Therefore, the scraper is always located in a position where it will perform its functions most effectively, regardless of the 30 movements of the tiltable roll. The means for forcing the scraper into engagement with the roll 3 comprises arms 18 secured to the ends of the rod 15, spring holding rods 19 passing through the lower ends of the 35 arms 18 and pivotally supported at 20, and springs 21 surrounding the rods 19. Each rod 19 is provided with a spring seat 22 engaging the lower portion of arm 18, and also with a spring seat 23. The springs 21 40 lie between the spring seats 22 and 23 so as to force the lower ends of arms 18 toward the side frames A, thereby forcing the scraper 13 into engagement with the roll 3. It will be noted that the springs 21 are not 45 intended to compel the scraper to follow the tiltable roll, such movements being due to the peculiar manner in which the scraping device is connected with the bearings B which tilt freely with said tiltable roll.

50 I claim:

1. A crushing mill comprising a pair of coöperating crushing rolls, one of which is tiltable, the tiltable roll being movable toward and away from the other roll, journals 55 extending from said tiltable roll, bearings fitted to said journals, guides to which said bearings are loosely fitted, said bearings being free to tilt with said tiltable roll, means for maintaining said bearings in firm engagement with said journals, and a tiltable scraping device fitted to said tiltable roll and connected to said bearings, thereby providing for said scraper being maintained in parallelism with the axis of the tiltable roll 60 when said roll is tilted.

2. A crushing mill comprising a pair of coöperating crushing rolls, one of which is tiltable, the tiltable roll being movable toward and away from the other roll, journals 70 extending from said tiltable roll, bearings fitted to said journals, guides to which said bearings are loosely fitted, said bearings being free to tilt with said tiltable roll, means for maintaining said bearings in firm engagement with said journals, arms extending 75 from said bearings, a rod mounted in said arms, a scraper secured to said rod and fitted to the periphery of said tiltable roll, thereby providing for said scraper being maintained in parallelism with the axis of the 80 tiltable roll when said roll is tilted, said scraper being free to tilt with said bearings, and yielding means for forcing said scraper into engagement with said tiltable roll.

3. A crushing mill comprising a main support provided with guides, a pair of crushing rolls including a tiltable roll provided with journals which lie between said guides, tiltable bearings fitted to said journals and loosely mounted between said guides, caps 85 arranged above said tiltable bearings and rigidly secured to said main support, said tiltable bearings being arranged between the rigid caps and the journals, yieldable elements fitted to the rigid caps and tiltable 90 bearings to maintain the latter in firm engagement with said journals, and a tiltable scraping device fitted to said tiltable roll and connected to said tiltable bearings, thereby providing for said scraper being 95 maintained in parallelism with the axis of the tiltable roll when said roll is tilted.

4. A crushing mill comprising a main support provided with guides, a pair of crushing rolls including a tiltable roll provided 105 with journals which lie between said guides, tiltable bearings fitted to said journals and loosely mounted between said guides, caps arranged above said tiltable bearings and rigidly secured to said main support, said tiltable bearings being arranged between the rigid caps and the journals, each of said caps being provided with a chamber for the reception of fluid under pressure, plungers extending from the chambers in said caps and fitted to said tiltable bearings, the contacting faces of said plungers and bearings being curved to allow the bearings to tilt freely with said tiltable roll, and a tiltable scraping device fitted to said 110 tiltable roll and connected to said bearings, thereby providing for said scraper being maintained in parallelism with the axis of the tiltable roll when said roll is tilted.

5. A crushing mill comprising a main support provided with guides, a pair of crushing rolls including a tiltable roll provided with journals which lie between said guides, tiltable bearings mounted between said 125 guides and fitted to said journals, said tilt- 130

able bearings being closely fitted to the opposing faces of the guides and provided with guide flanges normally separated from the guides to allow the bearings to tilt with the 6 tilttable roll, means for maintaining said tilttable bearings in firm engagement with said journals, and a tilttable scraping device fitted to said tilttable roll and connected to

said bearings, thereby providing for said scraper being maintained in parallelism 10 with the axis of the tilttable roll when said roll is tilted.

In testimony that I claim the foregoing I hereunto affix my signature.

HENRY HURTER.
